UNITED STATES PATENT OFFICE.

ERNST W. BUCKAU, OF NEW YORK, N. Y.

GOLF-BALL MOLD.

1,034,580.

Specification of Letters Patent.

Patented Aug. 6, 1912.

Application filed September 29, 1911. Serial No. 651,929.

To all whom it may concern:

Be it known that I, ERNST W. BUCKAU, a citizen of the United States, residing at New York, in the county of New York and 5 State of New York, have invented certain new and useful Improvements in Golf-Ball Molds, of which the following is a specification.

This invention relates to golf ball dies, 10 cups or molds, the object of the invention being to provide an improved golf ball mold which can be readily and inexpensively constructed and by means of which a perfectly round or spherical golf ball can be 15 obtained having any desired shape of brambles thereon.

It is well known in practice that golf balls provided with brambles are not always perfectly round, due to the manner in which 20 the same are molded. In other words, it has heretofore been the usual practice to provide the golf ball cup with openings or recesses to form the brambles on the ball; but these recesses or depressions in the cup have 25 to either be cut by hand or by machine, the depth of the cutting depending largely upon the manipulation of the operator or the machine, and it is extremely difficult, and frequently impossible, to get them all of the 30 same depth. Consequently, when the ball is molded it is not a perfectly round ball, as some of the brambles will project less or more than others, and therefore, as stated, a perfectly round ball is rarely obtained.

35 The object therefore of the present improvement is to provide a golf ball cup or mold by means of which an absolutely true, round ball can be obtained, for the reason that all of the brambles will necessarily be 40 of the same depth.

In the drawings accompanying and forming part of this specification, Figure 1 illustrates a pair of the golf ball cups or molds in juxtaposition as they are usually placed 45 when a ball is to be molded; Fig. 2 is a cross-sectional view of one of the molds; Fig. 3 is a view of the shell detached therefrom; Fig. 4 is a view of the shell casing or cup proper; and Fig. 5 is a detail view of a 50 portion of the golf ball having one form of brambles shown herein.

Similar characters of reference indicate corresponding parts throughout the figures of the drawings.

55 In carrying out the present improvement each cup or mold 2 is scraped to a gage so as

to form a perfect half sphere, being slightly larger than the ball to be molded. Fitting tightly into each of these molds or cups is a shell 3, which in practice is sweated into the mold or cup 2. This shell is of predetermined thickness throughout and is provided with openings or perforations of the desired form that the bramble is to have; for instance, the perforations may be circular, as 60 4, or they may be of star or other form, as 5. These openings or perforations extend entirely through the shell, and as the shell is of a uniform thickness throughout it follows that each of the perforations is of the 65 same depth as that of its companion perforations.

In practice it is preferable to project the edge of the shell a slight distance, say about .002 of an inch, above the upper edge of the 75 die or cup, as at 6, so that when pressure is placed upon the die cups to mold the ball the shell will be firmly forced into contact at all points with the wall of the die cup or mold and consequently there will be no leakage of 80 the material between the shell and its cup or mold. In other words, the material of which the ball is formed when forced into the openings of the shell cannot leak or run between the shell and the cup proper. 85

By forming the perforations in a shell, it will be immediately apparent that as the shell is the same thickness throughout it follows that the brambles must be of the same depth around the ball, so that a perfectly true, round ball is obtained when the material is placed between the two ball cups and the same are brought together under a pressure of many tons, as is the usual practice. 90

95 From the foregoing it will be observed that each half of the mold consists of a casting or casing member and a shell or shell member rigidly secured together, the latter provided with openings of any desired configuration to form the brambles, and the depth of which is determined by the thickness of the shell, so that all the brambles will be of precisely the same depth, and therefore a perfectly round ball is obtained. 100 105

In practice it is usual to provide some forms of molds with a plug in the end thereof, which is frequently used for impressing the name upon the ball, and in the present instance this form of mold is shown in the 110 drawings. In the present improvement, however, this plug is used for centering the

shell, and for which purpose the plug 7 is shown as projecting into the mold a sufficient distance to receive the shell, which is provided with an opening 8 for that purpose, and so center such shell, the inner end of the plug and the inner side of the shell being shaped to conform one with the other so that the adjoining edges thereof will be flush.

10 I claim as my invention:

1. A golf ball mold comprising a casing and a shell fitted thereto and having bramble forming openings extending therethrough.

15 2. A golf ball mold comprising a casing and a shell rigidly secured thereto and having bramble forming openings extending therethrough.

20 3. A golf ball mold comprising a casing and a shell fitted thereto and having bramble forming openings extending therethrough, said shell projecting slightly beyond the edge of the casing.

25 4. A golf ball mold comprising a cup made up of a casing and a shell, each of semi-spherical formation and secured together, the shell within the cup and having openings therethrough to form the brambles on the ball.

30 5. A golf ball mold comprising two cup-

shaped members, each comprising a casing and a shell fitted thereto and having openings therethrough all of the same depth throughout.

6. A golf ball mold comprising a cup-shaped member and a thin shell rigidly secured within said cup-shaped member and having openings therethrough conforming to the desired form of brambles on the ball, all of said openings being of the same depth.

7. A golf ball mold comprising a casing having a plug projecting thereinto beyond the inner wall thereof, and a shell fitted to the casing and having an opening for the reception of such plug.

8. A golf ball mold comprising a casing having a plug projecting thereinto beyond the inner wall thereof, and a shell fitted to the casing and having an opening for the reception of such plug, said shell having bramble forming openings extending therethrough.

Signed at 1821 Park Row Building, New York, N. Y., this 25th day of September, 1911.

ERNST W. BUCKAU.
